UNITED STATES PATENT OFFICE.

CHARLES E. MARTIN, OF MANSFIELD, OHIO.

BENDING CORRUGATED MATERIAL.

1,268,745.

Patented June 4, 1918.

Specification of Letters Patent. Application filed February 12, 1917. Serial No. 148,027.

To all whom it may concern:

Be it known that I, CHARLES E. MARTIN, a citizen of the United States of America, residing at Mansfield, in the county of

5 Richland and State of Ohio, have invented certain new and useful Improvements in Bending Corrugated Material, of which the following is a specification.

This invention relates to bending corrugated material.

The primary object of this invention is to bend corrugated material in such a manner as to form flanges thereon without subjecting the material to excessive strain, stress, 15 stretching, undue fracture or weakening of the fibers of the material.

Another object of this invention is to provide a method of forming flanges integral with the body portion of corrugated material in a manner that will not seriously affect the tensile strength of the material in forming the flanges.

A further object of this invention is to form flanges on corrugated material having 25 a series of alternate depressions and ridges, the depressions being formed concave and continuous with, but in alined angular relation to the convex portion of the corrugated material.

30 A further object is to provide means through the medium of flanges formed on corrugated material to connect sections of culvert pipes thereby constructing a culvert pipe of separate sections which before being connected permit of being closely and snugly packed together economizing in storage space and permitting the transportation of said sections closely and compactly packed together.

40 A further object consists in bending corrugated material at right angles to the body portion without subjecting it to undue strain to permit the flanges to extend around and cover the corners of a rectangular building or the like, thereby obviating the use of an extra corner piece.

I attain these and other objects by the method of making and constructing the article of manufacture, illustrated in the accompanying drawing, in which:—

Figure 1 is an exterior side view of two sections of corrugated material formed to be used for culvert pipes and provided with integral flanges showing same assembled 55 preparatory to being fastened together by bolts or the like.

Fig. 2 is a perspective view of Fig. 1 showing the culvert pipe sections nested, preparatory to shipping, transporting or shipping same in compact form.

60

Fig. 3 is a perspective view of Fig. 1 showing a portion of the interior, exterior and one end of the culvert pipe sections.

Fig. 4 is an interior view of a fragment of one of the culvert pipe sections showing 65 the relation and form of the face of the flange with respect to corrugations.

Fig. 5 is a perspective view of a conventional rectangular structure formed of sections of flanged corrugated material, showing 70 the method of using said material for covering structures of the form and type described.

The drawings show corrugated material bent in such a manner as to provide integral 75 flanges for fastening sections of the material together to provide culvert pipes and the method of using the sections of said material for covering rectangular structures or the like.

80 It will be noted that when the sections are used for covering a rectangular structure or the like, the flanged portions of each section overlap the unflanged end portions of the next succeeding sections at the corners of the structure.

In constructing the corrugated material A to provide culvert pipe sections, as shown in Fig. 4, a series of alternate concave portions 1 and convex portions 2 are formed as 90 shown. The corrugated material is then clamped securely at a pre-determined point so as to leave a margin of the corrugated material extending beyond the clamping means and in a position to be bent freely in 95 an angular relation to the body portion of the corrugated material which is held in a pre-determined position by the clamping means.

Pressure is exerted upon the margin of 100 the corrugated material that extends beyond the clamping means forming the angularly related flange C as shown clearly in Fig. 4. In exerting pressure upon the margin of said corrugated material to form the flange, 105 the pressure means or die is formed and arranged so as to form a flange on the corrugated material having a series of alternate concave depressions and convex ridges.

The pressure means or die is shaped and 110 designed to press against the convex portion of the corrugated material and form a

concave depression in line but in angular relation to the convex portions of the corrugated material and a convex ridge in line but in angular relation to the concave portions of the corrugated material, thereby forming a flange in angular relation to the body portion of the corrugated material having a series of convex ridges and concave depressions respectively on a plane with 10 each other.

Attention is called to the fact that in exerting the pressure upon the convex portions of the corrugated material preparatory to and in forming an integral angularly related flange upon the corrugated material with concave depressions in reverse relation, that undue stretching, straining and fracture of the fibers of the corrugated material are substantially eliminated and kinking of 15 the corrugated material prevented, as the excess or surplus material forming the convex portions of the body of the corrugated material follows the line of least resistance and forms a series of convex ridges on the 20 flange in line but in opposed relation to the concave depressions of the corrugated material.

In bending corrugated material to provide a flange as described, undue stress and 30 strain of the material incident to bending corrugated material in the conventional manner are eliminated.

In the operation described, the bending strain when a flange is being formed on the 35 corrugated material is equalized along the line indicated by reference letter D and the tensile strength of the corrugated material is no more affected than in the case of bending flanges on plane material.

40 It will be noted that economy in space, storage capacity and convenience and facility in shipping or transporting are accomplished by making culvert pipe in sections,

as described, and nesting them as shown in Fig. 2.

It is apparent that the rectangular form shown in Fig. 5 can be used for culvert pipe if desired. The form of flanged corrugated material shown in Fig. 5 however, is preferably used for covering buildings or the like, as described hereinbefore.

What I claim is:

1. The herein-described method of forming flanges on corrugated material having alternate ridges and depressions, consisting 55 in bending the edge of the material to form a flange and simultaneously forming such flange to present alternate ridges and depressions substantially similar to and uniform with such formations in the material 60 but of opposed registry, whereby each ridge and each depression of the material merges into a depression and a ridge respectively of the flange.

2. The herein-described method of forming flanges on corrugated material having alternate ridges and depressions consisting 65 in bending the edge of the material to form a flange, forming the flange with alternate ridges and depressions merging into and 70 registering with the non-similar formations of the material, the line of merger between such formations of the material and flange constituting the line of bend.

3. A corrugated strip having ridges and 75 depressions and an angularly related flange on one edge thereof having substantially similar ridges and depressions as the strip arranged in exact opposite order to such formations of the strip, the line of bend of 80 the flange constituting the plane of least projection of the material beyond the normal plane of the material to avoid fracture.

In testimony whereof I affix my signature.

CHARLES E. MARTIN.
